(57) **CLAIM**

The ornamental design for a sealing clip for bag, as shown and described.

DESCRIPTION

FIG. 1 is a perspective view of a sealing clip for bag showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a perspective view thereof in a position of use;

FIG. 9 is a perspective view thereof in use with a bag; and, FIG. 10 is a perspective view thereof joined with multiple other sealing clips for bag.

The elements shown in broken lines are for illustrative purposes only and form no part of the claimed design.

UNITED STATES PATENT AND TRADEMARK OFFICE
CERTIFICATE OF CORRECTION

PATENT NO. : Des. 531,016 S
APPLICATION NO. : 29/217814
DATED : October 31, 2006
INVENTOR(S) : Kobayashi

Page 1 of 7

It is certified that error appears in the above-identified patent and that said Letters Patent is hereby corrected as shown below:

The title page showing the illustrative figure should be deleted and substitute with the attached title page.

The drawing sheet, consisting of Fig. 1 - 10, should be deleted and replaced with drawing sheet, consisting of Fig. 1 - 10, as shown below.

In Drawing Sheet 1, replace Figure 1 with the figure as shown below.

FIG. 1

In Drawing Sheet 2, replace Figure 2 with the figure as shown below.

FIG. 2

UNITED STATES PATENT AND TRADEMARK OFFICE
CERTIFICATE OF CORRECTION

PATENT NO. : Des. 531,016 S
APPLICATION NO. : 29/217814
DATED : October 31, 2006
INVENTOR(S) : Kobayashi

It is certified that error appears in the above-identified patent and that said Letters Patent is hereby corrected as shown below:

In Drawing Sheet 3, replace Figure 3 with the figure as shown below.

FIG. 3

In Drawing Sheet 4, replace Figure 4 with the figure as shown below.

FIG. 4

UNITED STATES PATENT AND TRADEMARK OFFICE
CERTIFICATE OF CORRECTION

PATENT NO. : Des. 531,016 S
APPLICATION NO. : 29/217814
DATED : October 31, 2006
INVENTOR(S) : Kobayashi
